UNITED STATES PATENT OFFICE

141,010

DESIGN FOR A TOY CANNON

Adolph Keller, Glendale, Mo.

Application January 8, 1945, Serial No. 117,345

Term of patent 7 years

(Cl. D34—15)

To all whom it may concern:

Be it known that I, Adolph Keller, a citizen of the United States, residing at Glendale, in the county of St. Louis and State of Missouri, have invented a new, original, and ornamental Design for a Toy Cannon, of which the following is a specification, reference being had to the accompanying drawing, forming part thereof.

I claim:

The ornamental design for a toy cannon, as shown.

ADOLPH KELLER.
